UNITED STATES PATENT OFFICE.

JOHN C. NEVIUS, OF TRENTON, NEW JERSEY, ASSIGNOR OF ONE-HALF TO STANDARD RUBBER CO., OF TRENTON, NEW JERSEY, A CORPORATION OF NEW JERSEY.

TOOTH-BRUSH GUARD.

No. 851,550.

Specification of Letters Patent.

Patented April 23, 1907.

Application filed August 31, 1906. Serial No. 332,796.

To all whom it may concern:

Be it known that I, JOHN C. NEVIUS, of Trenton, in the county of Mercer and State of New Jersey, have invented certain new and useful Improvements in Tooth-Brush Guards; and I hereby declare that the following is a full, clear, and exact description thereof, reference being had to the accompanying drawings, which form part of this specification.

This invention is a novel device especially designed for use in connection with tooth brushes, nail brushes, and like toilet articles, to prevent the water, dripping from the brushes when in use, soiling the hands, cuffs, sleeves, etc., of the user; and also to serve as a support for the bristle-portion of the brush when the brush is laid down, so that the bristle-portion will be aired, and the brush can be more readily picked up; and also to serve as a means for supporting the brush when inserted in a rest without crushing the bristles,—and to also serve as a means for identifying individual brushes, for which latter purpose the devices are provided with initials or distinctive symbols so that each brush can be readily distinguished from others by its owner.

The invention consists in a small tubular rubber shield, preferably bell-shaped, and having its bore provided with an annular recess or pocket whereby the outer wall portions are thinned so that while the shield can be readily slipped on the handle of a brush or other device of larger diameter than the bore, it will not be materially distorted externally, as the thin walls at the ends of the bore can yield readily without causing any material deflection of the main body of the shield; and at the same time the shield will have two bearing points or constricting portions whereby it will be securely held in place upon the handle.

The shields may be made of distinctive colors, and further provided with initials, or symbols, whereby individual owners can readily distinguish their own articles to which the shields are applied.

The invention will be clearly understood from the accompanying drawings, in which—

Figure 1 is a perspective view of a shield attached to a tooth brush, and indicating its usefulness. Fig. 2 is an enlarged longitudi-

nal section through the shield as attached to a brush-handle. Fig. 3 is a transverse section on line 3—3, Fig. 2, looking in the direction of the arrows.

The shield A is preferably conical or bell-shaped, being larger at one end than at the other, and flared outwardly from the small to the larger end; the larger end being concaved, as at a. The shield has an axial opening or bore b, which is slightly less in diameter than the diameter of the handles it is intended to engage, so that it will clamp the latter when forced thereon. Intermediate the ends of the bore the shield is formed with an annular recess or pocket c which leaves the end walls d of the bore quite thin, compared with the length of the shield, and thus gives the shield two bearings at d, d, upon the brush handle H.

The shields are preferably made of Para-rubber, and of any desired color. And for purposes of identification they are preferably formed with distinctive symbols, such as initial letters on their outer faces, as indicated at e, in the drawings. When applied to a brush, the shield is slipped endwise on the brush handle, with the larger or concaved end a toward the bristle end of brush; the thin walls d will yield so that the shield can slip over irregularities in the surface of the handle, or past enlargements in diameter of the handle, to the desired position,—where it will be firmly held by reason of the natural constriction of the parts d.

In passing over larger or swell portions of the handle the parts d can yield readily, because they are substantially independent, by reason of the intermediate pocket or recess c which allows the parts d a certain amount of independent expansion and flexion without producing any appreciable or undesirable distortion of the body of the shield, which would be distorted if the bore b was of uniform diameter throughout. This pocket or recess c therefore is a very useful and important feature of the shield.

When the shield is in place, on a tooth-brush for example, as indicated in Fig. 1, it will prevent water running down the handle H onto the hands of the user, and soiling the linen of the user,—the water being caught by the shield and discharged as indicated in Fig. 1.

Obviously the shields can be applied to paint-brushes, pen-holders and various other implements and tools, and I do not therefore wish to be restricted to its use merely for brushes, as shields thus constructed are applicable to and useful on many other articles.

Having described my invention what I claim as new and desire to secure by Letters Patent is:

1. A shield for brushes, provided with a bore having an internal annular pocket or recess, substantially as described.
2. A rubber shield for brushes, having one end concave, and provided with a central bore having an internal annular pocket or recess, substantially as described.
3. A conical or bell-shaped rubber shield or guard, having its larger end concave, and provided with a central bore, the end walls of the bore being of less diameter than the interior portion of the bore, so that said end walls can flex or expand without affecting the main body of the shield.
4. A shield for brushes, comprising a rub-

ber body having one end concaved, and provided with a bore having an internal concealed annular pocket or recess, leaving the end walls of the bore flexible and self-adjusting whereby material distortion of the body of the guard is prevented when the guard is applied to a handle, substantially as and for the purpose described.

5. The herein described shield for brushes, comprising a conical or bell-shaped soft rubber body, having its larger end concaved, and provided with a bore of comparatively small diameter at its ends, and with an internal annular pocket or recess, leaving the end walls of the bore flexible whereby material distortion of the body of the guard is prevented when applied to a handle, substantially as and for the purpose described.

In testimony that I claim the foregoing as my own, I affix my signature in presence of two witnesses.

JOHN C. NEVIUS.

In presence of—
CHARLES H. ENGLISH,
JAMES D. BRADY.
